UNITED STATES PATENT OFFICE.

JEAN M. A. MONTCLAR, OF PARIS, FRANCE.

SAFETY-WICKET.

SPECIFICATION forming part of Letters Patent No. 245,005, dated August 2, 1881.

Application filed April 14, 1881. (No model.) Patented in France February 11, 1881.

To all whom it may concern:

Be it known that I, JEAN MARIE ARMAND MONTCLAR, of Paris, France, have invented an Improved Safety-Wicket for Doors, (for 5 which I have obtained Letters Patent of France, No. 141,114, for fifteen years, dated February 11, 1881,) of which the following is a specification, reference being had to the accompanying drawings, in which—

10 Figure 1 represents a face view of the upper wicket; Fig. 2, a vertical cross-section of part of a door containing the same; Fig. 3, an outer face view of the door containing my improved safety-wickets; Fig. 4, an inner face view 15 thereof, and Fig. 5 a cross-section of the same.

This invention relates to improvements in doors that lead to dwelling-houses or to dwellings in houses, and has for its object so to construct such doors that communication 20 may be had through them with parties standing outside without necessitating the opening of such doors, and so that larger or smaller packages may be received through such doors without opening them.

25 The invention consists, first, in providing the upper part of the door with a mortise or opening, over which is placed a metallic plate having a series of holes through which the persons standing on opposite sides of the door 30 may see and speak to each other, and through which letters and smaller parcels may be delivered, said plate being provided with suitable slides to close its openings. The inner side of the door has an additional plate with 35 a shutter thereto, which, when closed, closes said mortises on the inner side, excepting a slit left open for the delivery of letters. The lower part of the door has another larger opening, with means for closing the same on the 40 inside.

In the accompanying drawings, the letter *p* represents the door. In the upper part of the door, at such a height as to be in line with the head of a person of average size, is a mortise 45 or opening, more clearly shown in Fig. 2. Over the outer side of this opening is secured a metallic plate having upper openings, *b b*, and a lower slit, *c*. This plate is, by suitable bolts, *a*, firmly secured to the door. The openings *b* 50 can be closed by an interior slide, *b'*, which has similar openings and a handle at its inner side, (see Fig. 2,) by which it can be moved,

so as to bring its openings into line with the openings *b*, if communication with the outside is desired, or out of line to close said openings 55 *b*. The narrow slit *c* is for the delivery of letters and small parcels, and is closed by a plate, *c'*, which is hinged at the top and falls shut by its own weight. At the inner side of the door is fastened over the same mortise or opening 60 another metal plate containing a hinged shutter, *d*, which can be locked by a suitable bolt, *e*. Now, if any one should ring the bell, the occupant of the house or dwelling is not required to open the door; but, by first opening 65 the shutter *d*, and then moving the slide *b'*, communication may be had with the party outside, to insure that improper persons may not be admitted to the dwelling. Protection 70 is thus afforded against the intrusion of beggars, thieves, and the like, so that dwellings may safely be intrusted to the custody of servants, who, otherwise, might not be able to protect themselves against dishonest intruders.

The inner metallic plate has a slit obliquely 75 in line with the slit *c*, as shown in Fig. 2, so that letters can at all times be inserted through the door.

The lower part of the door has another mortise cut through it, much larger than the upper 80 mortise, and this lower large mortise or opening is closed by a movable gate, *f*, hung on hinges *g*, that are fastened to the door, and said gate *f* is braced by metal plates *g'*. Hooks *h* are attached to the door at the inner side 85 thereof, near the ends of the gate *f*, to receive a locking-bar, *k*, which rests also in a hook, *i*, that is attached to the gate *f*. By means of a suitable padlock, *l*, the bar *k* can be locked in its place to prevent its removal by unauthorized persons. When large packages are to be delivered, the occupant of the dwelling unlocks the lock *l*, removes the bar *k*, and opens the gate *f*, thus permitting the introduction 90 of such packages, and meanwhile the bar *k* constitutes a weapon of defense against persons that may seek entrance through the open lower panel against the wish of the occupant. To make this defense the more perfect, the bar *k* is provided with a hatchet attachment or 95 blade, as shown.

I claim—

1. The door *p*, provided with an upper mortise or opening and with a lower larger open-

ing, and combined with the two metallic plates at the upper mortise, one having openings *b* and *c*, slide *b'*, and gate *c'*, and the other having shutter *d*, and the lower opening having gate *f*, and means for locking the same in the door, substantially as specified.

5 2. The safety-wicket composed of two plates placed opposite an opening in the door, the

outer plate having openings *b* and slide *b'* and the inner plate having shutter *d*, substantially as specified.

J. M. ARMAND MONTCLAR.
